Application September 28, 1956, Serial No. 43,137

Term of patent 14 years

(Cl. D92—1)

Fig. 1 is a plan view of a puffed textile fabric showing our new design;

Fig. 2 is a sectional view of the fabric of Fig. 1 along the line 2—2;

Fig. 3 is a sectional view of the fabric of Fig. 1 along the line 3—3; and

Fig. 4 is a sectional view of the fabric of Fig. 1 along the line 4—4.

The design is embodied in a puffed textile fabric having a surface of raised puffs that are arranged in rows in the fabric. The rows are arranged in groups of three with the puffs in the intermediate row being staggered with respect to the puffs in the adjacent rows of a group. The puffs in the row in a first group that is adjacent the row in a second group are aligned with the puffs in said row in said second group in a direction transverse of the rows.

We claim:

The ornamental design for a puffed textile fabric, as shown and described.
